UNITED STATES PATENT OFFICE

BURT E. TAYLOR, OF MOUNT VERNON, NEW YORK, ASSIGNOR TO THE BORDEN COMPANY, OF NEW YORK, N. Y., A CORPORATION OF NEW JERSEY

APPARATUS FOR WASHING CANS AND THE LIKE

Application filed February 27, 1930. Serial No. 431,664.

This invention relates to improvements in apparatus for washing cans and the like and more particularly to can washing machines provided with means for washing can bottoms.

Heretofore there have been in use machines for washing cans, such as large milk cans, and some of these machines have been provided with means for carrying out other related operations, such as replacing the can covers after the washing of the cans. It is believed, however, that heretofore no provision has been made for washing the bottoms of the cans, which usually have at their lower edges flanges which keep the bottom proper above the ground or other supporting means thereby protecting the bottom against injury but leaving a space in which matter accumulates. The object of the present invention is to provide means for washing can bottoms and particularly means for this purpose which will be efficient in operation and which will be suitable for application to can washing machines in general. To this end the invention resides in the can washing apparatus hereinafter fully described and particularly pointed out in the appended claims.

The preferred form of the invention is illustrated in the accompanying drawings in which Fig. 1 is a vertical transverse section taken along the line 1-1 of Fig. 4; Fig. 2 is a detail plan view showing the part of the can supporting platform at which the washing of the can bottom takes place and also, partly in full lines and partly in dotted lines the spray device and controlling devices associated therewith; Fig. 3 is a view in section taken along the line 3-3 of Fig. 4; Fig. 4 is a horizontal sectional view taken along the line 4-4 of Fig. 1; and Fig. 5 is a detail view partly in section of part of the valve controlling means.

The can washing machine with which the can bottom washing device of the present invention is adapted to be associated may be of any usual or preferred construction and comprises a frame work of which only the discharge end is indicated in the drawings. During the washing operations the

cans 10 are advanced intermittently in inverted position along a runway including the parallel guide bars 11 by suitable can advancing means (not shown). This operation is effected in general in a manner usual in can washing machines and needs no further description. Eventually each washed can 10 is pushed off the rear ends of the guides or guide bars 11 and into a cradle 12 fixed on a horizontal rock shaft 13 extending transversely of the guide bars 11 just beyond the rear ends thereof. The cradle includes a seat 14 on which the top of the inverted can rests, a curved flange 15 extending upwardly from the seat and serving to position the top of the can on the seat and a central frame member 16 extending from beneath the seat. To assist in holding the can in position the cradle may also include a curved cross bar (not shown) secured to the member 16 and engaging the body of a can on opposite sides of said member 16 and the end (not shown) of the member 16 may be shaped to extend over the bottom of the inverted can to keep the can on the seat or support 14.

After the can has been placed in the cradle the latter is swung downwardly and after reversing the can deposits it in upright position (open end uppermost) on a platform 17 supported by uprights 18 forming part of the frame, the platform being provided with a slot 19 through which the cradle swings in freeing the can deposited on the platform.

Before the cradle passes through the platform in its return swing the can on the platform is moved out of the path of the cradle in a direction transverse with respect to the machine by suitable means which may comprise a finger 20 projecting outwardly from one of the links 21 of a sprocket chain 22 carried by sprocket wheels 23 fixed on shafts 23a so positioned that the upper reach of the chain travels in a slot 24 in the platform 17, said slot 24 being substantially perpendicular to the slot 19. Said shafts 23a may be journalled in brackets 24a of which the bracket or brackets at the receiv-

ing end of the chain may be adjustable to regulate the tightness of the chain.

Preferably the chain is also positioned so that the finger 20 engages the cam (just deposited by the cradle) at a point slightly to the rear of the axis of the can and in addition to moving the can transversely of the machine may move it somewhat toward the front of the machine and bring it into engagement with a transverse guide 25. Proper positioning of the can over the belt when deposited by the cradle may be assured by means including arms 26 and 27 at the rear of the can receiving position on the platform 17.

Eventually the can is moved along the guide 25 until it engages an arm 28 mounted to swing about a pivot 29 positioned at the side of the guide opposite to that engaged by the can, and normally urged by a spring 30 towards a stop 31, such as a pin extending upwardly from the platform 17. The spring 30 may be mounted in different ways but as here shown is used as a tension spring and is attached at one end to the upper end of a pin 32 projecting upwardly from the platform 17 and at the other end to the arm 28. The advance of the can by the finger 20 may be limited by any suitable means such as bars 33 extending rearwardly from the bar or guide 25, the lower bar 33 being positioned above the platform 17 at a sufficient distance to permit the arm 28 to pass between the same and the platform. As will be brought out hereinafter, the arm 28 may be used to control the washing of the bottom while the can is in the position indicated at the top of Fig. 4. To this end the platform 17 is provided at this location with a plurality of orifices 34 through which washing liquid such as water may be forced into engagement with the bottom of a can in the washing zone or position, the liquid being supplied through a chamber 35 formed at the bottom of the platform by a casing 36 and through a pipe 37 connecting the chamber 35 with any suitable source of supply. The flow of water through the pipe 37 is controlled by a suitable valve 38, for example, a self-closing valve having a stem or plunger 39 urged outwardly to close the valve but effective upon inward movement thereof to open the valve.

Control of the valve 38 may be effected by any suitable means which may include a member or rod 40 suspended from one end of a lever 41 mounted at the other end on a pivot 42 mounted on a fixed part of the frame of the machine. The lever is provided with a projection 43 which by means of a spring 44 connecting the lever with a fixed part of the machine, is held against a cam 45 located above the same and fixedly mounted on the shaft 13 which carries the cradle 12. Preferably this cam is shaped

so as to force the lever 41 and consequently the rod 40 downwardly sufficiently to depress the valve stem 39 and hold the same depressed while a dwell portion 46 of the cam is in engagement with the projection 43 of the lever. Of course such depression of the valve stem should occur only when there is a can in position to have its bottom washed and to this end the rod 40 is attached to the lever 41 so that while it must move up and down therewith it may be swung laterally into and out of alignment with the stem 39 of the valve 38. In Fig. 5 there is shown a suitable form of connection in which the rod 40 passes through an opening in the lever 41, said opening being flared outwardly at both top and bottom of the lever, and the actual connection between the rod 40 and the lever 41 is effected by nuts 47 threaded on said rod and provided with tapered portions fitting into the flared portions of said opening through the lever 41, the adjustment of the parts being maintained by any suitable means such as a lock nut 48.

Connection between the swinging arm 28 and the rod 40 may be effected in any suitable manner. For example, the arm 28 may be one arm of a bell crank 49 of which the other arm 50 has an opening 51 through which passes the rod 40. It will be seen that the arm 28 acts as a detector or feeler to detect the presence or absence of a can in the bottom washing zone and to control the bottom washing means accordingly.

After the washing of the bottom of the can in the bottom-washing position has been completed, the can is removed from that position by means of a finger 52 projecting outwardly from a link 53 of a chain 54 carried by sprocket wheels 55 on shafts 56 journalled in brackets 57 of which the outer ones project downwardly from guide bars 58 in the form of angle irons and serving as a guideway along which the cans can be removed from the bottom washing zone, the inner brackets 57 being secured to the platform 17 at its lower face adjacent to a slot 59 through which the chain 54 passes. In order that the finger 52 may effect suitable engagement with the inner surface of the flange 60 at the bottom of a can in the bottom washing zone, the slot 59 extends into this washing zone and makes necessary a corresponding slotted construction of the casing 36. In this connection it should be understood that the slot 24 for the chain 22 also extends into this washing zone and makes necessary a corresponding change in the construction of the casing 36.

The arrangement for engagement with the inside of the flange at the bottom of a can is necessary in view of the fact that in order to effect satisfactory washing of a can bottom water must be applied to as much of

the surface as is practicable and that, if the chain were arranged so that the finger 52 would engage the can at the other side thereof, there would have to be a slot extending 5 clear across the washing zone. Furthermore such a slotted arrangement would prevent the use of the chain 54 in the inclined arrangement illustrated, in which the cans taken from the bottom-washing zone are carried 10 up inclined guide bars 58. At the upper end of the conveyer or chain 54 the cans are discharged upon the tops of a plurality of rolls 61 rotatably mounted in a stand 62 and which may be actuated in any suitable 15 manner. The finger 52 is effective only to carry a can to the upper end of the chain, for, after the can arrives there, the finger will be withdrawn downwardly thus releasing 20 the can. This difficulty may, however, be avoided by providing an additional finger 63 spaced behind the finger 52 so as to rise above the surface of the platform just after the can has been removed therefrom and to follow the can up the guideway and, upon 25 release of the can by the finger 52, to engage the can and shove it far enough along the extended ends of the guide bars 58 to rest on the roll at the adjacent end of the set of rolls.

30 As indicated on Figs. 1 and 3, the position at which the bottom of a can is washed is also the position at which a cover 64 is placed in the open end or mouth of the can. The covers 64 in moving to such position 35 travel through a runway including two guide bars 65 substantially parallel to the guide bars 11 of the can runway and constructed and arranged so that a cover moved off the rear end of the cover runway will drop 40 into the mouth of a can in the cover replacing or bottom washing position. The movement along the runway may be effected by any suitable means which may include a reciprocating bar 66 and pivoted fingers or 45 pawls 67.

The actuation of the chains or conveyors 22 and 54 may be effected in any suitable manner. For example, the chain 22 may be 50 actuated through the shaft 23a nearer the bottom washing position and this shaft may be actuated from the adjacent shaft 56 through intermeshing bevel gears 68 and 69, of which the gear 68 is on the shaft 23a and the gear 69 is on the shaft 56. Preferably 55 the conveyor chain 54 is used only as a conveyor (its upper reach being supported by a channel member 70) and the upper and outer shaft 56 is driven from the lower shaft 56 by means of a sprocket chain 71 passing 60 around sprocket wheels 72 fixed on the corresponding shafts 56. As indicated in Figs. 3 and 4, the lower shaft 56 is driven through a sprocket wheel 73 fixed thereon and a 65 sprocket chain 74 cooperating with the wheel

73 and connected with a suitable source of power (not shown).

The rocking of the shaft 13 to swing the cradle 12 may be effected by any suitable means which, as illustrated in Fig. 1, may 70 include a sprocket wheel 75 fixed on the shaft 13 at the left side of the machine (as seen in Fig. 1) and connected by means of a sprocket chain 76 with a sprocket wheel 77 farther to the front of the machine and 75 connected directly with a gear 78 rotatable about the same axis. The gear 78 meshes with a gear 79 on a shaft 80 extending to the other side of the machine where it is provided with a pinion 81 fixed thereon and a 80 bracket or yoke 82 pivoted thereon and effective to hold a rack 83 (slidable therein) in effective engagement with the pinion while permitting the rack to swing about the axis 85 of the pinion.

The means for actuating the rack is not shown but may include a member or rod extending from one end of the rack and pivotally connected with a pin eccentrically mounted on a member or disk fixed on the end of a main driving shaft extending across the top of the machine to the other side thereof where it is provided with a gear meshing with a gear on a shaft parallel to the main shaft and carrying a sprocket 95 wheel which cooperates with the sprocket chain 74.

What I claim as new and desire to secure by Letters Patent is:

1. In a can washing machine, means for 100 discharging a can from the main washing zone with its open end lowermost, means for reversing the can into upright position with its open end uppermost, and means for washing the lower side of the bottom of the can while in position with its open end uppermost.

2. In a can washing machine in which a can is discharged from the main washing 110 zone in inverted position, means for reversing the can into upright position with its open end uppermost, means for shifting the reversed can to a bottom washing zone, washing means at said bottom washing zone, a valve for controlling the supply of 115 liquid to said washing means, means for intermittently opening said valve when operatively related thereto, and means for controlling the relation between the valve and the valve opening means so that the valve opening means is normally ineffective to open the valve but is rendered effective for this purpose by movement of a can into the bottom washing zone.

3. In a can washing machine in which a can is discharged from the main washing 125 zone in inverted position with its open end lowermost, a support, means for receiving the inverted can and depositing it on the support with its open end uppermost, and 130

means for washing the bottom of the can when placed in bottom washing position on said support including normally closed valve means for controlling the supply of water thereto, controlling means normally disconnected from the valve means but connected operatively therewith upon movement of the can to the bottom washing position and means for actuating said controlling means to open said valve and render the bottom washing means effective.

4. In a can washing machine, means for discharging a can from the main washing zone with its open end lowermost, means for reversing the can into upright position with its open end uppermost, a support on which the can is deposited when so reversed, means in a bottom washing zone on said support for washing the outer surface of the bottom of the can, means for conveying the can from the position where deposited to said bottom washing zone, means for conveying the can from the bottom washing zone after the bottom washing period has elapsed, a self closing valve for controlling the supply of liquid to the bottom washing means, means including a member acting intermittently to engage the valve and open the same during each bottom washing period, and can controlled means normally acting to prevent such intermittently acting member from engaging and operating said valve but caused to permit such action by the presence of a can in the bottom washing zone.

5. In a can washing machine, means for discharging a can from the main washing zone with its open end lowermost, a support, means for receiving the inverted can and depositing the can at a predetermined position on the support with its open end uppermost, means for delivering a cover to said can in said predetermined position, means for washing the bottom of the can when in said predetermined position on the support with its open end uppermost including valve means for controlling the supply of water, operating means normally disconnected from the valve means but operatively connected therewith upon movement of the can to said predetermined position and means for actuating said operating

means to open the valve and render the bottom washing means effective while the can is in said predetermined position.

6. In a machine for washing cans having at their bottom ends circular flanges which normally hold the bottoms of the cans above supports on which the cans rest, a platform on which each can is delivered with its open end uppermost and which has a substantially circular bottom washing zone of substantially the diameter of a can and provided with a plurality of perforations to direct liquid against the bottom of a can in the bottom washing zone, means including a pipe for supplying liquid to said perforations, a self-closing valve for said pipe and including a member by which the valve may be opened, means for conveying each can to the bottom washing zone, means for conveying each can away from the bottom washing zone at the termination of a bottom washing interval, a plunger, a feeler controlled by the movement of the can into said zone, feeler controlled means normally holding said plunger out of position for operating the valve member but rendered effective upon engagement of the feeler by a can to render the plunger effective for operation of the valve member, and means for actuating said plunger during each bottom washing period.

7. In a can washing machine, supporting means, means for delivering a can into a predetermined position on the supporting means with its open end uppermost, means for delivering a cover to each can in said predetermined position, and means for washing the bottom of the can while in said predetermined position with its open end uppermost including means for directing water upwardly against the outer surface of the bottom of the can, means including a valve for controlling the supply of water to the directing means, operating means normally disconnected from the valve means but connected therewith by movement of the can to said predetermined position and means for actuating said operating means to open the valve and render the bottom washing means effective.

BURT E. TAYLOR.
